CLAIM

The ornamental design for a fire pit assembly as shown and described.

DESCRIPTION

FIG. 1 is a perspective view of a fire pit assembly showing my new design with the lid in the open position;

FIG. 2 is another perspective view thereof;

FIG. 3 is another perspective view thereof;

FIG. 4 is another perspective view thereof;

FIG. 5 is a front view thereof;

FIG. 6 is a back view thereof;

FIG. 7 is a left side thereof;

FIG. 8 is a right side view thereof;

FIG. 9 is a top view thereof; and

FIG. 10 is a bottom view thereof.

FIG. 11 is a perspective view thereof with the grate bracket stowed underneath in the rails and the lid in the alternative closed position; and,

FIG. 12 is another perspective view thereof.

The broken lines shown in the drawings are included for the purpose of illustrating portions of the article that form no part of the claimed design.
